UNITED STATES PATENT OFFICE.

NORVAL RUNSTETLER, OF SEATTLE, WASHINGTON.

NON-SKID SAFETY DEVICE.

1,391,413.

Specification of Letters Patent. Patented Sept. 20, 1921.

Application filed August 25, 1920. Serial No. 405,892.

To all whom it may concern:

Be it known that I, NORVAL RUNSTETLER, a citizen of the United States, residing at Seattle, in the county of King and State of Washington, have invented a certain new and useful Improvement in Non-Skid Safety Devices, of which the following is a specification.

My invention relates to sanding devices which are particularly adapted for use upon automobiles.

I shall describe my invention in connection with automobiles, although it can be used with slight and obvious changes upon other vehicles, if desired.

The principal object of my invention is to provide such a device in which the sand will be freely delivered to a trap and held therein until it is positively expelled by the admission of fluid pressure behind the sand in the trap.

Another object is to provide an improved valve for controlling the admission of exhaust gases from the automobile engine to expel the sand from the trap.

My invention comprises those novel parts and combinations thereof which are shown in the accompanying drawings, described in the specification, and particularly defined by the claim terminating the same.

In the accompanying drawings I have shown my invention in the form which is now preferred by me.

Figure 1 is a section and partial elevation through my device.

Fig. 2 is an elevation of the valve casing and the valve operating means.

Fig. 3 is a section on the line 3—3 of Fig. 1.

Where sand is to be expelled by the exhaust from an internal combustion engine I secure a valve casing 2 in the exhaust line from the engine. The pipe 11 represents this exhaust pipe. It is secured in the casing 2 by suitable means, such as the screw 16. The casing 2 is provided with two outlets, one serving as the normal exhaust or leading to the muffler (not shown) and the other leading to a sand trap.

Between the port leading from the pipe 11 and the normal outlet of the casing, I provide a valve seat 4, and between the pipe 11 and the sand trap 9 I provide a second valve seat 5. Within the casing and reciprocable between the two valve seats, which are shown herein as opposed, is a plunger 3,

formed with valves at each end adapted to seat upon the respective seats 4 and 5 to close them selectively. Suitable means for actuating the valve are provided, those shown consisting of a lever 6 pivoted upon the casing at 12 and engaging the stem of the valve, and a bell crank lever 8 pivoted at 15 upon the casing, and connected to the lever 6 by a link 7, which is pivoted at 13 upon the lever 6 and at 14 upon the lever 8. The lever 8 may be swung by any suitable means, preferably manual means, operable from the driver's seat, to reciprocate the valve 3 through the motion of the lever 6. It may be found desirable to employ, in connection with the sand trap to be later described, another form of two-way valve and I do desire to limit myself to the construction described other than as defined in the appended claim.

The sand trap 9, which is connected to one outlet from the valve casing 2, is shown as formed of a section of pipe. It extends first laterally from the casing 2 and is then bent downwardly and then preferably upwardly to form a gooseneck. The upper wall of the downwardly bent portion should be at least as low as the lowermost wall of the straight portion leading from the casing 2. The outer end of the pipe 9, being bent upwardly, assists in retaining the sand in the gooseneck. A supply pipe 10, leading from any suitable source of supply of sand (not shown), delivers sand to the gooseneck by gravity.

Normally the valve 3 would be seated upon the seat 5 to permit the exhaust to pass out of the uppermost outlet from the casing 2. Sand running down the pipe 10 gathers in the gooseneck 9 until this is filled, as shown in Fig. 1, but does not run out of the delivery nozzle, the pipe being sufficiently long and upturned to prevent. When it is desired to deliver sand to the path of the automobile, the lever 8 is swung on its pivot to raise the valve 3 to the seat 4. This motion closes the normal outlet of the exhaust and applies the full force thereof to expel the sand from the gooseneck 9. The sand is thus blown first from the top of what is gathered in the gooseneck, in this way providing a passage for the exhaust and permitting the remainder of the sand to be sucked through to be delivered where desired. Additional sand will be supplied through the pipe 10 unless a valve is em-

- ployed to prevent this. Whether or not such a valve is used is largely immaterial, though I prefer to omit this. When the need for sand has passed, the valve 3 may be again 5 reseated upon the seat 5, thus closing off the pressure in the gooseneck 9 and permitting the exhaust to follow its normal course. Sand again gathers by gravity in the gooseneck 9, to be used as needed.
- 10 It will be observed that in this system one valve only, and that to control the exhaust, is required. The gooseneck 9 automatically controls the amount of sand supplied with the first blast of the exhaust and automatically 15 gathers and holds sufficient sand for the purpose, but prevents the accumulation of an excess thereof. The valve employed might be any ordinary two-way valve, although that described is my preferred construction. In vehicles which are propelled 20

otherwise than by an internal combustion engine, the valve would control only the admission of other fluid pressure, as compressed air, to the sand trap. The exhaust outlet from the casing 2 would then naturally be 25 omitted, or employed for another purpose.

What I claim as my invention is:

In a sanding device for automobiles, a sand trap and means for delivering sand thereto, a valve casing adapted to be connected to the engine exhaust, and having two outlets, one being connected to said trap, said casing having two opposed seats, a plunger reciprocable in the casing and having valves at its opposite ends adapted to seat selectively upon said valve seats, to permit normal exhaust or to admit air behind the sand in said trap to expel it. 30 35
